COUPLER

William J. Regan, Pittsburgh, Pa., assignor to
McConway & Torley Corporation, Pittsburgh,
Pa., a corporation of Pennsylvania

Application June 28, 1934, Serial No. 732,898

11 Claims. (Cl. 213—130)

My invention relates to car couplers and is particularly designed to provide a strong and reliable operating structure of comparatively light weight which may be easily dismantled and assembled and wherein the knuckle-opener and lock are spring actuated.

A coupler constructed according to my invention is well suited for application to passenger cars and advantageous in that the locking mechanism thereof is adapted to be actuated by a rotary type of release mechanism or by a pull rod type of release; and said locking mechanism is well adapted to be moved to unlocked position by means of a simple lever, and a completely fitted coupler may be conveniently carried on the train for use in case of emergency.

The principal feature of the invention consists in providing the coupler with a horizontally sliding lock which is normally maintained in locked position by means of a spring, and combining therewith a horizontally rotatable knuckle-opener to which is pivotally connected a link between which and said lock the spring is operatively interposed.

A further feature of the invention consists in so forming and relating the coupler knuckle, knuckle-opener and lock that the head of the coupler may be provided with a bearing surface for the lock which is located opposite the portion of the lock with which the knuckle contacts, thereby affording adequate support for the lock against forces communicated thereto by the knuckle and at the same time avoiding any tendency of the lock to shift angularly and thereby bind during an unlocking operation.

There are other features of invention residing in the particular forms of elemental construction and combinations of parts, as will hereinafter appear and be pointed out in the claims.

In the drawings illustrating the invention:

Figure 1 is a plan view of a coupler embodying the invention, arranged for a pull rod type of release mechanism for the coupler lock.

Figure 2 is a view in side elevation of the construction shown in Figure 1.

Figure 3 is a detail view partly in plan and partly in horizontal section, the parts being in the position they occupy when the coupler is locked.

Figure 4 is a detail view corresponding to Figure 3 but illustrating the positions assumed by the parts during an unlocking movement of the coupler lock and just before the knuckle is released for opening movement.

Figure 5 is a detail view partly in plan and

partly in horizontal section illustrating the construction shown in Figures 1 to 4, inclusive, the parts being in the positions they occupy when the knuckle has been rotated by the knuckle opening device.

Figure 6 is a detail sectional view on the line 6—6 of Figure 5, the parts being in the positions they occupy when the knuckle is fully open.

Figure 7 is a transverse sectional view on the line 7—7 of Figure 3.

Figure 8 is a detail plan view of the coupler lock.

Figure 9 is a detail sectional view on the line 9—9 of Figure 8.

Figure 10 is a detail sectional view on the line 10—10 of Figure 9.

Figure 11 is a detail plan view of the knuckle-opener lever and associated link by which it is actuated.

Figure 12 is a side elevational view of the parts shown in Figure 11.

Figure 13 is a plan view of the form of lock releasing lever embodied in the construction shown in Figures 15, 16 and 17.

Figure 14 is a detail sectional view of the lock releasing lever on the line 14—14 of Figure 13.

Figure 15 is a plan view of the coupler as arranged for a rotary type of release.

Figure 16 is a side elevational view of the construction shown in Figure 15.

Figure 17 is a detail view in transverse section of the mechanism illustrated in Figures 15 and 16.

Figure 18 is a plan view of the coupler as arranged for a type of release intended for emergency use.

Figure 19 is a side elevational view of the construction shown in Figure 18.

Figure 20 is a detail view, partly in elevation and partly in transverse section, of the construction shown in Figures 18 and 19.

In the drawings 1 indicates the head and 2 is the shank or stem of the coupler. The stem of the coupler is preferably formed at its rear end with an opening 3 for receiving a tail pin 45 serving to pivotally connect the coupler to the draft gear carried by the car with which it is associated.

The pivoted knuckle 4 of the coupler is preferably mounted on the coupler head by a knuckle pin 5 which may advantageously be of the downwardly removable type, said pin being normally supported in assembled position by an underlying headed pin or supporting member 6 which passes through suitable openings in the lower

part of the coupler head and is retained in position by a cotter 7. The tail 8 of the knuckle is relatively short and is formed with a vertically disposed bearing face 9 which is adapted to 5 cooperate with the adjacent bearing face 10 of the horizontally sliding lock 11 thereby to retain the knuckle in closed or coupled relation.

The lock 11 is mounted within the head 1 so as to be slideable in the direction of length of 10 the longitudinal axis of the coupler. It is provided at its forward end with a locking block portion which, when the parts are in locked position, is interposed between the bearing face 9 of the knuckle tail 8 and an oppositely disposed bearing surface 12 with which the coupler head is provided on its interior on the guard-arm side. The bearing face 12 extends forwardly so as to be co-extensive with the surface of 15 the knuckle which engages the lock, thus enabling the forces which are transmitted to the lock from the knuckle to be efficiently resisted without tendency of twisting the lock. The surface 12 extends rearwardly for a distance sufficient to support and guide the lock throughout 20 its entire range of movement. For guiding the opposite side of the lock the lower portion of the coupler head is provided on its interior with an upstanding lug 13 which may advantageously be formed as a part of the pivot boss 14 for 25 positioning the knuckle opener 15 in the coupler head. The surface of this lug which is adjacent the sliding lock 11 is disposed vertically in a plane parallel to the knuckle engaging face 10 of the lock and cooperates therewith in all operating 30 positions the lock may assume.

The lock is provided with a portion 16 which extends rearwardly beyond the coupler head 1 into the coupler stem 2, such portion of the lock preferably being of somewhat less width 40 than the forward portion of the lock which receives the transverse thrusts from the knuckle. To assist in guiding the lock 11 during its sliding movements the coupler body is provided on its interior at approximately the junction of its 45 head and stem with a rib or lug 17 which is adapted to cooperate with the neighboring side of the rear extension 16 of the lock.

The sliding lock 11 is provided with a rearwardly opening pocket 18, and its rearwardly extending portion 16 is formed with vertically aligned longitudinally extending slots 19 which are closed at their rear ends and communicate with said pocket. Within the pocket of the lock a coiled spring 20 is disposed. The forward end 55 of this spring bears against the sliding locking block 11 while its rear end bears against a spring seat 21 which is slidably mounted within the pocket or chamber 18 of the lock. This spring seat is preferably provided with a forwardly extending cylindrical pin which, by entering the bore of the spring, serves to maintain it in assembled position and restrain it against any buckling tendency. The spring seat has a vertically extending cylindrical opening 22 for receiving 60 the correspondingly formed downwardly extending pin or pintle 23 with which the link 24 that connects the spring seat and knuckle-opener 15 is provided at its rear end. As shown in the drawings, the rearward extension 16 of the 65 coupler lock may be provided with horizontally aligned slots or openings 25, thereby affording clearance for the spring 20 with a minimum width of the lock extension 16, and at the same time decreasing the amount of metal in the 70 lock. The knuckle opener 15 is of the bell-crank

lever type. It is formed with a curved arm 26 which extends behind the knuckle tail 9 for operating therewith to rotate the knuckle to open position, and it is provided with an arm 27 for pivotal connection to the forward end of the link 24. The arm 27 extends over the upper face of the sliding coupler lock 11 and thereby serves to prevent it moving upwardly while the arm 26 which engages the knuckle is preferably at a lower elevation, the two arms being integrally united by a cylindrical sleeve portion 28 which is perforated to receive a pivot pin 29 by which the knuckle-opener is rotatably mounted on the coupler head.

The upper arm 27 of the knuckle-opener is 15 pivotally connected to the link or operating bar 24, being for that purpose preferably bifurcated at its outer end to receive the forward end of the link. The cooperating ends of the knuckle-opener and link are perforated to receive a pivot 20 pin which may advantageously be a rivet 30.

As a means for actuating the sliding lock 11 to effect an unlocking movement thereof, the coupler is provided with a lock releasing member which is positioned beneath the coupler head 25 and is pivotally connected thereto, preferably by the pivot pin 29 upon which the knuckle opener 15 rotates. The drawings disclose three desirable forms of this horizontally rotatable lock releasing member, each form including a 30 lever arm to receive applied power and a vertically extending pin or finger which is spaced from the axis of rotation of the lock releasing member and projects upwardly through the lower wall of the coupler head into the recess in the 35 lock 11.

In the construction shown in Figures 1 to 7, inclusive, the rotary lock releasing member 31, which is journaled upon the pivot pin 29, is provided at the outer end of its arm 32 with a vertically extending pin 33 which passes upwardly through an arcuate slot 34 in the bottom wall of the coupler head and enters a recess 35 in the lock 11, the said recess being of a size to permit the pin 33 to cooperate with the lock without binding and preferably being open toward the guard-arm side of the coupler head. For actuating it, the lock releasing lever 31 is fashioned with a lever arm 36 which is provided at its outer end with an opening to permit the connection thereto of a pull rod (not shown) extending to the side of the car. This form of rotatable lock releasing member is especially suited for operation from the left side of the car by means of a pull rod.

Figures 13 to 17, inclusive, show a lock releasing lever 37 of a form especially suitable for actuation by a rotating rod 38 extending to the side of the car and provided at its outer end with a handle 39 which pulls up and out through an arc when actuated to effect an uncoupling operation. This release lever 37, like the release lever 31, is pivotally mounted beneath the coupler upon the pivot pin 29. It provides an arm 40 from which a pin 41 extends upwardly through the arcuate slot 34 in the bottom wall of the coupler head and into the recess 35 of the sliding coupler lock 11, these details of construction being similar to features heretofore described with reference to Figures 1 to 7 of the drawings. The actuating arm 42 of this release lever is preferably curved rearwardly, and it is adapted to be rotated by the rotatable uncoupling rod or lever 38, the latter being for that purpose provided with a bent inner end forming a downwardly extending arm 70 75

43 which overlaps the rear face of the lever arm 42. The inner end of the uncoupling rod or lever 38 is rotatably supported in an elongated loop 44 which is cast integrally with the lower wall 5 of the coupler head at the knuckle side of the latter, and forms a support and fulcrum for the inner end of the uncoupling lever. A suitable form of bracket for supporting the outer end of the uncoupling lever 38 is disclosed in the 10 Miliken Patent No. 1,507,244, Sept. 2, 1924. After the outer end of the lever has been positioned in the bracket it is impossible for the inner end thereof to become disconnected from the coupler head.

15 Figures 18 to 20, inclusive, illustrate the coupler as equipped with a form of lock releasing lever 45 which is well adapted to permit a completely fitted coupler to be carried in the baggage car or tool box compartment of the train for 20 emergency use. This form of horizontally rotatable lock releasing lever is formed with an arm 46 at the outer end of which is a handle portion 47. About midway of its length the arm 46 is fashioned with an upwardly extending portion terminating in a pin 48 which projects through the arcuate slot 34 in the bottom wall of the coupler head and enters the recess 35 in the sliding coupler lock 11. The release lever 45 is pivotally mounted on the pin 29. To prevent the possibility of 25 the lock releasing levers 31, 37 and 45, respectively, being clamped tight between the lower headed end of the pin 29 and the underface of the coupler head when the nut 49 at the upper end of the pivot pin is tightened, the lower end 30 of the pin is somewhat enlarged in diameter, as indicated at 50, to thereby form an upwardly facing shoulder which, by coming into contact with the coupler head, insures freedom of rotary movement for the lock releasing lever.

35 40 In assembling the coupler the lock 11, spring 20, spring seat 21, and the attached link or bar 24, and knuckle-opener 15 are first assembled as a unit. This is accomplished by first inserting the spring 20 into the opening or pocket 18 of the lock and then placing the spring seat 21 in position. The spring 20 is then compressed until the hole 22 in the spring seat overlaps the rear ends of the top and bottom walls 19 of the coupler lock for a distance sufficient to permit the 45 vertically extending pintle or finger 23 of the connecting link 24 to be inserted through the top slot of the lock, into the hole in the spring seat, and into the bottom slot of the lock. As so assembled these parts may be placed as a unit in 50 their working position by passing them through the throat or opening in the front face of the coupler head. The assembling operation is completed by placing in position the form of release lever that is to be employed, passing the 55 bolt or pivot pin therethrough and through the pivot pin opening in the knuckle-opener 15, and finally applying the nut 49.

60 When the lock releasing lever, 31, 37, or 45, as the case may be, is caused to perform an unlocking rotation, the upwardly extending pin with which it is provided forces the lock 11 rearwardly toward unlocked position. As the spring seat 21, which is connected to the knuckle opener 15 by the link or bar 24, cannot retreat until the 65 unlocking movement of the lock has progressed far enough to free the knuckle 4 for outward rotation, this unlocking movement of the lock 11 effects a compression of the spring 20. When the lock 11 has moved rearwardly far enough to 70 lock the knuckle the spring 20 expands, forcing 75

the spring seat 21 rearwardly. The rearward movement of the spring seat, by pulling upon the link 24 which is pivotally connected to the knuckle opening lever 15, causes the latter to retreat and thereby throws the knuckle 4 to open position, the parts at the end of that operation assuming the position illustrated in Figure 5.

75 During a closing movement of the knuckle 4 the tail 8 of the knuckle presses against the arm 26 of the knuckle opener 15 causing the latter to rotate. This rotation of the knuckle opener pulls the link 24 and spring seat 21 forwardly, thereby compressing the spring 20 between the spring seat and the lock. During the closing movement of the knuckle the lock 11 engages the rear end of the tail 8 of the knuckle and as soon as the knuckle is fully closed the spring 20 immediately forces the lock 11 to locked position.

10 Having thus described my invention, I claim:

1. A car coupler involving a coupler head, a 20 knuckle pivotally mounted on said head, a lock for said knuckle adapted to move rearwardly to unlocked position, a horizontally rotatable knuckle-opener lever pivotally mounted on said head, a spring acting upon said lock, a spring seat for said spring movable with respect to said lock, said spring being interposed between said spring seat and said lock, and a link pivotally connected to said knuckle-opener lever and said 25 spring seat and adapted to communicate movement from said spring seat to said knuckle-opener lever.

30 2. A car coupler involving a coupler head, a knuckle pivotally mounted on said head, a lock for said knuckle adapted to move rearwardly to 35 unlocked position, horizontally rotatable means for opening said knuckle, a spring for moving said lock to locked position, a link, a spring seat interposed between said link and spring and movable with respect to said lock and link, said spring being operatively interposed between said lock and said spring seat and being adapted to cause 40 a knuckle opening rotation of said knuckle opening means, and rotatable lock releasing means for moving said lock to unlocked position, said link 45 being connected to said knuckle-opening means and to said spring seat, and said knuckle opening means and said lock releasing means being mounted on the coupler head and having a common pivotal axis.

50 3. A car coupler involving a coupler head, a knuckle pivotally mounted on said head, a horizontally slid able lock for said knuckle adapted to move rearwardly to unlocked position, a horizontally rotatable knuckle-opener pivotally mounted upon said head, a spring compressible by an unlocking movement of said lock, a spring seat for said spring movable with respect to said lock, and a link device operatively interposed between said spring and said knuckle-opener and pivotally connected to the latter and to said 55 spring seat.

60 4. A car coupler involving a coupler head, a knuckle pivotally mounted on said head, a horizontally slid able lock for said knuckle, a horizontally rotatable knuckle-opener lever, a spring for moving said lock to locked position, a spring seat for said spring movable with respect to said lock, said spring being interposed between said lock and said spring seat, a link device interposed between and pivotally connected to said spring seat and said knuckle-opener lever, and means for moving said lock to unlocked position.

65 5. A car coupler involving a coupler head, a knuckle pivotally mounted on said head, a slid-

- able lock for said knuckle adapted to move rearwardly to unlocked position, a horizontally rotatable knuckle-opener lever pivotally mounted on said head, said knuckle-opener lever having an arm extending over said lock for preventing upward movement of the latter, a spring for moving said lock to locked position, means actuated by said spring for causing rotation of said knuckle-opener lever, said means being pivotally connected to said arm, and means for moving said lock to unlocked position.
6. A car coupler involving a coupler head, a knuckle pivotally mounted on said head, a lock for said knuckle adapted to move rearwardly to unlocked position, a horizontally rotatable knuckle-opener lever pivotally mounted on said head and having an arm extending over said lock for preventing upward movement of the latter, a spring acting at its forward end against said lock, and means actuated by said spring for rotating said knuckle-opener lever, said means extending forwardly from the rear end of said spring to said arm and being movably attached to the latter.
7. A car coupler involving a coupler head, a knuckle pivotally mounted on said head, a lock for said knuckle adapted to move rearwardly to unlocked position, a horizontally rotatable knuckle-opener lever pivotally mounted upon said head, a spring acting upon said lock, a spring seat for said spring slidably mounted on said lock, and a link device pivotally connected to said spring seat and said knuckle-opener lever, said lock being provided with an elongated slot, said spring seat having a pivot pin opening, and said link device being provided with a pivot pin which projects through said slot into said opening.
8. A car coupler involving a coupler head, a knuckle pivotally mounted on said head, a slideable lock for said knuckle adapted to move rearwardly to unlocked position, said lock being provided with a rearwardly opening pocket and having adjacent its rear end a slot communicating with said pocket, a spring disposed within the pocket of said lock, a spring seat slidably mounted within said pocket and against which said spring bears, means movably connected to said spring seat and said knuckle-opener, said means including a pin projecting through said slot and engaging said spring seat, and means for moving said lock to unlocked position.
9. A car coupler involving a coupler head, a knuckle pivotally mounted on said head, a horizontally slideable lock for said knuckle adapted to move rearwardly to unlocked position, a horizontally rotatable knuckle-opener lever pivotally mounted on said head, a spring for moving said lock to locked position, a spring seat cooperating with said spring, and a link operatively interposed between said spring and said knuckle-opener lever and pivotally connected to said spring seat, said head being provided on its interior with a bearing surface for supporting said lock, said bearing surface being disposed transversely opposite the portion of said lock which engages said knuckle when the coupler is locked.
10. A car coupler involving a coupler head, a knuckle pivotally mounted on said head, a slideable lock for said knuckle adapted to move rearwardly to unlocked position, said head being provided with laterally spaced surfaces forming guides for said lock, a horizontally rotatable knuckle-opener lever pivotally mounted on said head and having an arm extending over said lock for preventing upward movement of the latter, a spring for moving said lock to unlocked position, a spring seat for said spring movable with respect to said lock, and a link extending between and pivotally connected to said arm and said spring seat.
11. A car coupler involving a coupler head, a knuckle pivotally mounted on said head, a slideable lock for said knuckle adapted to move rearwardly to unlocked position, a horizontally rotatable knuckle-opener lever pivotally mounted on said head and having an arm extending over said lock to limit upward movement of the latter, a spring for moving said lock to locked position, means operatively interposed between said knuckle-opener lever and spring for rotating said knuckle-opener lever, said means being movable with respect to said knuckle-opener lever, a lock releasing member positioned beneath the coupler head and having a portion engaging said lock to move the latter to unlocked position, and a pivot pin forming a pivotal mounting for said lock releasing member and for said knuckle-opener lever.

WILLIAM J. REGAN.
